UNITED STATES PATENT OFFICE.

JOHN F. LEIDECKER, OF ALAMEDA, CALIFORNIA.

PAPER DISPENSER.

Application filed February 20, 1923. Serial No. 620,203.

My invention is an improved paper dispensing device.

In my copending application, Serial No. 599,795, I have disclosed a paper dispenser.

5 The objection to this device is that when the paper is drawn out of the frame, and the bale is in the forward position, any decrease in the pull on said paper will cause the bale to return to the rear position, thus destroying the effect of the machine which is to provide a surplus tag of paper.

The object of this invention is to provide a catch for the bale whereby said bale is held in the operating position until the paper has 15 been cut, at which time the bale is released.

Another object of my invention is to provide a means whereby the paper roll is kept in a central position between the two supporting posts.

20 In the drawing in which my invention is illustrated:

Figure 1 is a transverse sectional view of my paper dispenser.

Figure 2 is a side view of the same.

25 Figure 3 is an enlarged fragmentary sectional view of the bale catch.

Figure 4 is a fragmentary plan view of the bale catch.

Figure 5 is a side view of the paper roll 30 supporting shaft and the centralizing washer secured thereto.

Figure 6 is an end view of the same.

Referring more particularly to the drawing: the numerals 1 and 2 indicate a pair of 35 upright roll supporting posts which are joined at the top by a horizontal bar 3 and secured at their base to a suitable surface. Detachably mounted on the posts 1 and 2 is a paper guide frame 4 which comprises side 40 walls 5 and 6. The walls 5 and 6 are secured to the posts 1 and 2 at their lower end by bolts extending through ears 7 and 8 on the walls 5 and 6 respectively and into the posts 1 and 2.

45 A downwardly inclined guide plate 9 is secured to the sides 5 and 6 and a hook 10 is formed on the upper end of said guide which is adapted to hook over the bar 3 and thereby hold the frame 4 in position 50 therein.

A bale 11 is mounted in the frame 4 across the top of which is formed a wooden friction contact member 12. The bale 11 is journaled in the sides 5 and 6, the arms of the 55 bale being bent to present small horizontal sections 13' adapted to be introduced

through slots 13" in the sides and to be supported by plates 13"" secured to the sides after the bale has been placed; and counterweights 13 are secured to the ends thereof below the journals to keep said bale normally in a vertical position.

The front wall of the frame 4 is formed in two sections 14 and 15; the upper section 14 is securely fastened to the sides 5 and 6 while the lower section is pivoted thereto in the following manner: Metal plates 16 are secured to the ends of the section 15, which plates are pivoted at 17 to the sides 5 and 6. The plates 16 extend upwardly from section 15 adjacent the section 14, and within the frame 4.

Pivoted to the tops of each of the plates 16 are lugs 18 which are adapted to engage fingers 19 which extend from each end of the friction member 12. Stop plates 20 are secured to the sides 5 and 6 and extend into the path of the section 15 to limit its forward movement. A knife 21 is secured to the lower edge of the section 15 against which the paper is torn. As the paper is drawn horizontally out of the frame 4 the section 15 is swung outwardly and the plates 16 move rearwardly. As the bale 11 moves forward the fingers 19 slip under the lugs 18 and are held by the latter as long as the knife 21 is pressed forward by the paper as shown in Figure 3. After the paper is torn the section 15 tends to drop back into the position indicated in Figure 1 and during its return motion the lugs 18 first slightly depress the fingers 19 and then lose their hold on the same so that the bale is free to swing back into its vertical position. A pair of rollers 22 and 23 are journaled adjacent the bar 3 to guide the paper. A pressure bar 24 rests against the paper roll to limit the unreeling thereof.

It is very essential that the paper be kept in a central position between the posts 1 and 2. To accomplish this I provide a pair of discs 25 which fit over the end of the supporting shaft 26 against the ends of the paper roll and between said roll and the posts 1 and 2.

100 The slack forming mechanism may be applied to machines for intermittently feeding webs of paper or other material, without cutting the web adjacent the section 15 by omitting the knife 21. In this general application the rollers 22 and 23 would function as "in" guides and the outlet between

the guide plate 9 and the section 15 function as an "out" guide, and the friction contact member 12 functions as a movable web carrier.

5 The operation of such a paper feed is as follows:—

Presuming the position of the paper is as shown in Figure 1, when tension is put on the loose hanging end by pulling it the paper is drawn tight against the web carrier 12 and swings it to the position shown in Figure 3, where it is latched and held while there is tension on the web. When the tension on the web is removed by stopping the pulling the carrier 12 may move back to its first position. Thus when there is no tension on the web it occupies a path, the shortest between the "in and out" guides, which may be likened to one side of a triangle. When the web is pulled it follows a path, as shown in Figure 3 a much longer distance between the "in and out" guides, which may be likened to the other two sides of the triangle: and as two sides of a triangle are longer than the third side, when the tension on the web is removed and the carrier moves to the position of Figure 1 a slack is produced.

Having described my invention, I claim:

30 1. In a paper dispenser, a frame, paper supporting posts, means for securing said frame to said posts, said frame having side walls and a front wall, a bale pivoted in said side walls over which the paper is adapted to travel and move forwardly when the paper is withdrawn, means for returning said bale to its rear position when the paper is released, said front wall being formed with an upper section and a lower section, said

lower section being pivoted to the side walls, 40 plates secured to said lower section, lugs pivoted to said plates, fingers secured to said bale which are adapted to be engaged by said lugs when the bale is in the forward position with the paper being withdrawn. 45

2. In a paper dispenser of the character described, means for supporting a roll of paper, a yoke pivoted and weighted at its free ends to normally present its cross-member above the roll so as to allow the end of the paper to be guided thereover and frictionally engaging the paper so as to swing downward with the same as the latter is unrolled, a cutting edge for the paper, and a pivoted support for the latter adapted to have its lower section swung forward by the paper while its upper section swings backward into engagement with the yoke for holding the latter during the cutting action. 55

3. In a paper dispenser of the character described, means for supporting a roll of paper, a yoke pivoted and weighted at its free ends to normally present its cross-member above the roll so as to allow the end of 60 the paper to be guided thereover and frictionally engaging the paper so as to swing downward with the same as the latter is unrolled, a cutting edge for the paper, a pivoted support for the latter comprising a 70 lower section adapted to be swung forwardly by the paper, and arms extending above the pivot having lugs thereon and fingers extending from the yoke adapted to be engaged by the lugs as the cutting edge is 75 swung forward for cutting action.

In testimony whereof I affix my signature.
JOHN F. LEIDECKER.
